US0D1027198S

(12) **United States Design Patent** (10) **Patent No.:** **US D1,027,198 S**
(45) **Date of Patent:** **** May 14, 2024**

(54) **MUSCLE STIMULATOR**

(71) Applicant: **HAIKOU LILI INVESTMENT CO., LTD.**, Haikou (CN)

(72) Inventor: **Junyuan Chen**, Haikou (CN)

(73) Assignee: **HAIKOU LILI INVESTMENT CO., LTD.**, Haikou (CN)

(**) Term: **15 Years**

(21) Appl. No.: **29/883,437**

(22) Filed: **Jan. 30, 2023**

(30) **Foreign Application Priority Data**

Aug. 16, 2022 (CN) 202230535712.9

(51) **LOC (14) Cl.** **24-01**

(57) **CLAIM**

The ornamental design for a muscle stimulator, as shown and described.

DESCRIPTION

FIG. 1 is a perspective view of a muscle stimulator showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the muscle stimulator that form no part of the claimed design.
